(57) **CLAIM**

I claim the ornamental design design for a locking pliers jaw, as shown and described.

DESCRIPTION

FIG. 1 is a right side view of our new design for a locking pliers jaw, the left side view being identical;

FIG. 2 is a front view showing my new design shown in FIG. 1;

FIG. 3 is a back view showing my new design shown in FIG. 1;

FIG. 4 is a top view showing my new design shown in FIG. 1;

FIG. 5 is a bottom view showing my new design shown in FIG. 1;

FIG. 6 is a perspective view showing my new design shown in FIG. 1;

FIG. 7 is a right side view of a second embodiment of my new design for a locking pliers jaw, the left side view being identical;

FIG. 8 is a front view showing my new design shown in FIG. 7;

FIG. 9 is a back view showing my new design shown in FIG. 7;

FIG. 10 is a top view showing my new design shown in FIG. 7;

FIG. 11 is a bottom view showing my new design shown in FIG. 7;

FIG. 12 is a perspective view showing my new design shown in FIG. 7;

FIG. 13 is a right side view of a third embodiment of my new design for a locking pliers jaw, the left side view being identical;

FIG. 14 is a front view showing my new design shown in FIG. 13;

FIG. 15 is a back view showing my new design shown in FIG. 13;

FIG. 16 is a top view showing my new design shown in FIG. 13;

FIG. 17 is a bottom view showing my new design shown in FIG. 13; and,

FIG. 18 is a perspective view showing my new design shown in FIG. 13.

The portions shown in broken lines are not part of the claimed design but show the environment in which the design is associated.
